DESIGN FOR AN INK WELL

Meyer Haberman, New York, N. Y.

Application December 6, 1944, Serial No. 116,748

Term of patent 3½ years

(Cl. D74—8)

To all whom it may concern:

Be it known that I, Meyer Haberman, a citizen of the United States, residing at the Bronx, New York, New York, in the county of Bronx and State of New York, have invented a new, original, and ornamental Design for an Ink Well, of which the following is a specification, reference being had to the accompanying drawing, forming a part thereof.

In the drawing:

Fig. 1 is a perspective view of an ink well, showing my new design;

Fig. 2 is a side elevational view;

Fig. 3 is a top plan view;

Fig. 4 is a bottom plan view; and

Fig. 5 is an end elevational view of the same.

I claim:

The ornamental design for an ink well, as shown.

MEYER HABERMAN.
